UNITED STATES PATENT OFFICE.

CHARLES E. SCRIBNER, OF CHICAGO, ILLINOIS, ASSIGNOR TO THE WESTERN ELECTRIC MANUFACTURING COMPANY, OF SAME PLACE.

AUTOMATIC SIGNALING-CIRCUIT FOR TELEPHONE-EXCHANGES.

SPECIFICATION forming part of Letters Patent No. 251,955, dated January 3, 1882.

Application filed March 28, 1881. (No model.)

To all whom it may concern:

Be it known that I, CHARLES E. SCRIBNER, of Chicago, Illinois, have discovered certain new and useful Improvements in Automatic 5 Signaling-Circuits for Telephone-Exchanges, of which the following is a full, clear, concise, and exact description, reference being had to the accompanying drawing, forming a part of this specification.

10 My invention consists of an insulated arm attached to the lever of the automatic switch. This arm vibrates with the lever, and while in motion holds open the circuit of the return-wire. An annunciator in the circuit of the 15 return-wire at the central office is thus caused to notify the listening operator that a subscriber has taken down or hung up a telephone. The operator is thereby relieved from the necessity of keeping the telephone constantly at 20 his ear.

In the drawing, Figure 1 shows my invention.

A is the central office, and B a subscriber's outfit, shown in detail. C and D are also subscribers' offices. a b c are telephone-lines of the three subscribers. d is the common return-wire. The arm e is attached to the lever of the automatic switch, and vibrates with it, moving between the contact-points f and g.

30 It will be seen that while the arm is moving from one contact-point to another the circuit of battery h in the common return-wire d will be held open. The shutter i of the annunciator at the central office in the circuit of the 35 wire d is thus thrown down, and the local circuit of bell k closed. Bell k will thus ring until the shutter is restored.

It is evident my invention may be adapted to a normally-open circuit. The line may be run to many stations, and provided at each 40 with a contact-point near the insulated arm attached to the switch, so arranged that the circuit will be closed for a short time while the switch is passing from one position to the other.

45 In Fig. 2, Sheet 2, the line d' is shown connected with the annunciator l and with point m near the insulated arm e' attached to the lever at the subscriber's station. The weight of the telephone holds the lever in position 50 indicated by the full lines. On taking down the telephone the lever assumes the position indicated by the dotted lines. The arm is thus for a moment in contact with contact-spring m, and the shutter i' is thus thrown 55 down, closing the local circuit of the bell.

I claim—

1. The circuit breaking or closing arm e, in combination with the automatic switch and a normally open or closed return-circuit, and an 60 annunciator and battery included in said circuit, whereby listening operator is notified when a subscriber takes down or hangs up a telephone.

2. The insulated arm attached to the switch-lever, in combination with a circuit including a battery and annunciator, whereby a signal is given automatically when the switch-lever is passing from either position to the other, as and for the purpose set forth.

CHARLES E. SCRIBNER.
